UNITED STATES PATENT OFFICE.

OSCAR M. LEICH, OF GENOA, ILLINOIS, ASSIGNOR TO CRACRAFT, LEICH ELECTRIC COMPANY, OF GENOA, ILLINOIS.

ANNUNCIATOR.

1,116,598.

Specification of Letters Patent. Patented Nov. 10, 1914.

Application filed March 4, 1912. Serial No. 681,443.

To all whom it may concern:

Be it known that I, OSCAR M. LEICH, a citizen of the United States, residing at Genoa, in the county of Dekalb and State 5 of Illinois, have invented a certain new and useful Improvement in Annunciators, of which the following is a full, clear, concise, and exact description, reference being had to the accompanying drawings, forming a 10 part of this specification.

My invention relates to annunciators and is of more particular advantage in connection with annunciators for telephone exchange purposes although my invention is of course not so limited. My invention may, for instance, be very advantageously employed in the manufacture of what in the art are termed combined drops and jacks, and I have chosen for illustrating my invention herein such a combined drop and jack constructed in accordance with my invention. The following specific description of this drop and jack must therefore not be understood as limiting my invention, but must 20 be taken as illustrative, as many modifications within the scope of my invention may be made. In the specific form illustrated herein however, the combined drop and jack is preferably built in connection with a 25 framework of punched material, which framework carries the operating parts with the exception of the shutter, the framework and shutter coöperating however by both being mounted upon a suitable front 30 plate designed for their accommodation. The combined drop and jack illustrated herein has, however, certain new magnetic features, notably the arrangement of the device in such a way that a removable coil 35 and core may be employed whose installation may be effected without adjusting the shutter controlling armature. These and allied features however are set forth and claimed in my co-pending application Serial No. 40 681,442, filed March 4, 1912. The remaining novel features of the device are claimed in this present application.

My invention herein contemplates improved structural features whereby the various elements are more readily accessible and more open to inspection. In conformity herewith, a skeleton framework is utilized to mount the various parts in such a way that little, if any, of the operating mechanism is

obscured. Further, new night bell features 55 are shown. These and other features of my invention will be readily apparent from the construction which will now be described in connection with the accompanying drawings illustrating one form of carrying out 60 my invention, in which:

Figure 1 is a front view of a strip of drops and jacks constructed in accordance with my invention; Fig. 2 is a top view of a portion of the strip, one individual device 65 having its coil removed; Fig. 3 is a side view partly in section of one of my improved drops and jacks; Fig. 4 is a rear view of a portion of a strip of drops and jacks; Fig. 5 is a view of the coil, shell and 70 armature separated to reveal their inter-relation; Fig. 6 is a sectional view on lines A—A of Fig. 1; Fig. 7 is a view on line B of Fig. 3 showing the upper portion of the structure; Fig. 8 is an end view of the shell; 75 Fig. 9 is a detail of construction; Fig. 10 is a sectional view on line C—C of Fig. 2; and Fig. 11 is a detail top view of the restoring spring.

In accordance with my invention I provide a front plate 1 which is adapted for mounting in a switchboard of the telephone type and which front plate carries the shutters 2. A strip of insulation 3 rests against the rear side of this front plate 1 and insulates this plate from the various drop and jack parts mounted thereon, which parts as will appear in detail are mounted upon a suitable skeleton framework 4. This skeleton framework is held in place upon the 90 front plate 1 by means of the screws 5, 5 and 6, 6, which screws project through the front plate 1 and are insulated therefrom as will appear later. The framework 4 has the downwardly extending arm 7 and forwardly extending parallel arms 8, which arms 8 are bent at their forward edges parallel to the front plate 1 and are then engaged by the screws 5, 5. An armature 9 is pivoted upon a spindle 10, which spindle 100 is mounted in the arms 8, 8. The armature 9 is provided with an anti-sticking tip 11 riveted thereto, and carries a drop shutter controlling arm 12 to be explained more in detail later. A partition 13 is held by means 105 of screws 14 between the sides 8, 8 of the framework 4 by virtue of the forwardly extending arms 15 of this partition. This par-

tion 13 has a central opening 16 for purposes that will appear presently. A pole piece 17 is riveted to the partition 13 by means of rivets 18. This pole piece has an aperture registering with the aperture 16. A coil 19 has a protruding core 20 adapted to project through the central aperture in the pole piece 17 and partition 13, all as explained more in detail in my said co-pending application. The core 20 has fiber end plates 21, 21, and the rear fiber end plate 21 is provided with contact terminals 22, 22 to which the terminals of the coil are connected, these terminals being brought out through holes 23, 23. A split shell 24 shown more clearly in Fig. 8 is provided for the coil 19 and is removable therewith. The coil and core are mounted to the framework by means of an arm 25 mounted on the core between the insulating disks 26, 26, which arm 25 has a slotted extension 27 held in place by means of the screw 28 to a depending arm 29 of the framework 4. The shell 24 is cut away at 30 to accommodate the arm 25. Slotted links 31 and 32 extend respectively from the contact elements 22 to screw threaded extensions 34 and 33.

A plate 35 extending downwardly of the framework 4 carries circuit changing springs 36, 37 and 38, the screw threaded extension 33 being part of the spring 36, and the screw threaded extension 34 being part of the spring 37. A restoring spring 39 bifurcated to form two arms 40, 40 is held by means of the rivets 41, 41 to the horizontal portion of the framework 4. This restoring spring carries an insulating lug 42. The partition 13 has sidewardly extending arms 43, 43 which engage interlocking slots provided in the arms 8 so that these extensions 43 in connection with the screws 14 prevent rotation of the partition 13. The downwardly extending plate 35 is riveted by means of the extensions 44 to the horizontal section of the skeleton framework 4. Suitable insulation 45 is provided to insulate the springs 36, 37 and 38 from the said plate 35. The restoring spring 39 has downwardly extending arms 46, 46 which by means of the rivets 47 hold the insulating lug 42 in place.

My improved removable ferrule consists of a substantially diamond shaped plate 48 having a cylindrical extension 49 secured thereto and which projects through the opening 50 provided in the front plate for this cylindrical extension. A strip of insulation 51 is interposed between the plate 48 and the front plate 1. The screws 6, 6 properly insulated from the metallic parts, with the exception of the framework 4, hold this plate 48 in position. It will be seen that the cylindrical extension 49 extends through an opening in the framework 4 so that this framework does not metallically

engage the ferrule portion 49. The ferrule is thus insulated from all of the metallic portions of the structure and by reason of this arrangement as just described may be removed for purposes of replacement should this ferrule in the course of its use become worn. The restoring spring 39 projects through an opening 52 in the front plate 1 and is adapted to engage a circular apron 53 depending from the shutter 2. The shutter has arms 54 through which the spindle 55 passes, upon which spindle said shutter is rotatably mounted and which spindle is held in place by arms 56 provided upon the plate 57, which plate 57 is held in place by the screws 5. The plate 57 is insulated from the front plate 1 by a strip of insulation 58 and the screws 5, being properly bushed, also prevent metallic contact between the plate 57 and the front plate 1. The strip of insulation 3 likewise serves in this connection for insulating purposes. The shutter arm 12 extends through an opening 59 in the front plate 1 and by means of its latch engages the shutter 2, passing through said shutter through the opening 60. The upper portion of this shutter right over the opening 60 is bent inwardly as shown at 61 and this maintains the shutter slightly removed from a vertical position. The arm 12 has a hump 62 so that as this arm moves upwardly in response to the actuation of the armature 9 it tends to throw the shutter 2 outwardly. The night alarm contact spring 63 held in place by means of the screws 64 is mounted upon, but insulated from, the front plate 1 and has downwardly extending lugs 65, 65 which also are bent forwardly to project into the opening 52 provided in the front plate. A thin contact spring 66 held between the insulating strip 58 and the front plate 1 has a downwardly extending contact element 67 which is adapted to be engaged by the downwardly extending arms 68 of the shutter 2 so that when this arm 68 engages the extension 67, this extension is forced into contact with the night alarm spring 63, thereby closing the night alarm circuit as is well understood. It will be seen from this that all of the parts are mounted on the skeleton framework 4 with the exception of the shutter portions. This skeleton framework 4 is of an open character and permits inspection of all of the parts whenever the coil and shell are removed. Furthermore this framework carries the pivotally mounted armature in association with the permanently mounted pole piece and carries the springs 36, 37 and 38 in such a way that these springs occupy a vertical position to prevent lodgment of dust thereon. It will likewise be seen that the insulating portion 42 of the restoring spring 39, which is the part that receives the wear on account of 130

the plug, may be readily replaced by the insertion of a new portion 42. The extremely long spring action of this restoring spring will also be apparent and this permits a 5 large movement for restoring purposes. All of the parts as will be apparent are insulated from the front plate 1 and the ferrule which is also a part likely to receive a 10 large proportion of wear is readily replaceably by a new ferrule.

It will, of course, be understood that as before stated modifications may be readily made without departing from the spirit of the invention herein disclosed, the structure 15 herein being merely illustrative.

What I therefore claim as new and desire to secure by Letters Patent is:

1. In a device of the character described the combination with a front plate, of a 20 framework secured to said front plate, a removable coil and shell carried by said framework, a shutter structure secured to said front plate, and means for securing said shutter structure and said framework 25 conjointly to said front plate.

2. In a device of the character described the combination with a front plate, of a framework secured to said front plate, a removable coil and shell carried by said 30 framework, a shutter structure secured to said front plate, means for securing said shutter structure and said framework conjointly to said front plate, and insulating 35 means interposed between said front plate and said framework, and shutter structure.

3. In a device of the character described, the combination with a front plate, of a framework mounted on and insulated from 40 said front plate, said framework having a downwardly extending arm, means for attaching said arm to the front plate, said framework having two upwardly extending sides, an armature pivoted between said sides, forward extensions for said sides, 45 and means for securing said forward extensions to said front plate, said framework forming a trough for the reception of a coil and shell.

4. A device of the character described 50 having a front plate, a framework having two sides and a bottom and open at the top mounted to said front plate, forming a trough for the reception of a removable

coil and shell, and an armature mounted between the sides of said framework. 55

5. A device of the character described having a front plate, a framework having two sides and a bottom and open at the top mounted to said front plate, forming a trough for the reception of a removable 60 coil and shell, a downwardly extending plate provided upon said framework, and an armature mounted between the sides of said framework.

6. A device of the character described 65 having a front plate, a framework having two sides and a bottom and open at the top mounted to said front plate, forming a trough for the reception of a removable coil and shell, and a removable coil having 70 a shell mounted on said framework.

7. A device of the character described having a front plate, a framework having two sides open at the bottom and top mounted to said front plate, a removable 75 coil having a shell mounted on said framework, and an armature pivoted between the sides of said framework.

8. In a device of the character described, the combination with a front plate, of a 80 framework mounted on and insulated from said front plate, a removable coil and shell carried by said framework, said framework having a downwardly extending arm, means for attaching said arm to the front plate, 85 said framework having two upwardly extending sides, an armature pivoted between said sides, forward extensions for said sides, and means for securing said forward extensions to said front plate, said framework forming a trough for the reception of a coil and shell. 90

9. A device of the character described having a front plate, a framework having two sides and a bottom and open at the 95 top mounted to said front plate, forming a trough for the reception of a removable coil and shell, and a removable coil and shell mounted on said framework.

In witness whereof, I hereunto subscribe 100 my name this 19th day of February, A. D., 1912.

OSCAR M. LEICH.
